UNITED STATES PATENT OFFICE.

BAGSTER ROADS SEABROOK, OF MISHAWAKA, INDIANA, ASSIGNOR, BY MESNE ASSIGNMENTS, TO LYRADION MANUFACTURING COMPANY, OF MISHAWAKA, INDIANA, A CORPORATION OF DELAWARE.

TALKING MACHINE.

Application filed September 26, 1918, Serial No. 473,316. Renewed May 28, 1921.

To all whom it may concern:

Be it known that I, BAGSTER ROADS SEABROOK, of the city of Mishawaka, Indiana, have invented certain new and useful Improvements in Talking Machines, of which the following is the specification.

The invention relates to improvements in talking machines and the principal object of the invention is to construct a talking machine having the sound box tube mounted entirely independent of the horn, thereby providing an air opening at the receiving end of the horn and to arrange such that air can be admitted to the horn either by forced draft or otherwise through the opening provided.

A further object is to construct the neck of the horn in a special manner and to supply a supporting post for the horn at the neck to reinforce and strengthen the same.

With the above objects in view the invention consists essentially in the arrangement and construction of parts hereinafter more particularly described and later pointed out in the appended claims, reference being had to the accompanying drawings in which:

Fig. 1 represents a vertical sectional view centrally through a cabinet form of talking machine with my invention installed.

Fig. 2 represents an enlarged vertical sectional view through the horn chamber, the section being taken in the plane denoted by the line X-X' Fig. 1 and looking towards the bracket.

Fig. 3 represents an enlarged horizontal sectional view through the tube, the section being taken at Y-Y' Fig. 1.

Fig. 4 represents a vertical sectional view through the neck of the horn and adjacent parts, the section passing centrally and longitudinally of the horn.

Fig. 5 represents an enlarged horizontal sectional view through the upper end of the neck of the horn.

Fig. 6 represents an enlarged sectional view through the horn, the section being taken at Z-Z' Fig. 4.

In the drawings like characters of reference indicate corresponding parts in the several figures.

1 represents the case or body of a cabinet talking machine which is fitted with the usual hinged top 2 and is provided with the customary record storage compartments 3

and 4 entered from the front of the machine through the doors 5.

7 and 8 represent two cross partitions within the case, which partitions enclose what might be termed the horn chamber 9.

Here I wish it to be particularly noticed that the partitions as well as the bottom 1' of the case stop short of the back of the case and butt against a vertical cross board 10, which board forms with the back and side walls of the cabinet an inlet air shaft or passage 11 leading from the bottom of the machine to the rear end of the horn chamber.

12 represents the turn table of the machine which is suitably mounted on the partition 7 and carries the usual record 13. 14 is the sound box tube fitted with the sound box 15 provided with the usual stylus or needle 15'.

The parts above described, with the exception of the air passage 11, are of ordinary construction and for this reason a further description of them is not herein given. It is however to be understood that the turn table is operated by a motor (not shown) and that the record is placed on the turn table 80 and the stylus on the record to produce the sound in the usual manner. Further the connection of the sound box tube to the partition 7 is a common one, such being by way of an outwardly turned flange 16 swivelly attached to the receiving collar 17 secured to the partition.

The delivery end of the sound box tube or tone arm opens to the upper end of a cylindrical tube 18 permanently mounted in the partition 7 and extending downwardly into the back of the horn chamber. To the back of the case, I secure permanently a special bracket 19 which lies horizontally just below the lower end of the tube 18. The bracket is formed from an upper plate or board 20 and a lower plate or board 21, the two being securely bolted together as indicated at 22.

The plate 21 receives the upper end of the horn 23 which is fastened firmly, such as by gluing, to the board, and it will here be observed that the top board overhangs the under one and is fitted with a tapering opening 24 in which I secure permanently a tapering or cone shaped tube 25 which has the lower end flush with the end of the horn and the upper end extending above, receiving

and spaced from the lower end of the tube 18. In this way I provide an air inlet opening 26 between the horn chamber and the interior of the horn.

5 In the present application I have shown the opening 26 as non adjustable but in this connection wish to state that in a copending application Serial # 237,582 filed May 31, 1918 I have shown it as adjustable so that 10 the amount of air admitted at this point can be controlled. Under ordinary conditions however the extent of the opening would be standardized so that the various sizes of machines would have openings to suit the 15 condition existing.

The horn 23 has the inner end fastened, as above explained, to the bracket and the outer or delivery end is mounted in the usual way in the front of the casing. The neck of 20 the horn is reinforced by making it thicker than the delivery or flaring end and in this connection reference is made particularly to Figures 4, 5 and 6 of the drawings where it will be seen that the upper end at the bracket 25 is, comparatively speaking, very thick and heavier at the front than at the back, and that below the bracket it gradually decreases in thickness on the front side but retains the same thickness at the back. This formation 30 is an important one as I find that by reinforcing in this manner I greatly improve the value of the horn in so far as the delivery of the sound waves are concerned.

Directly beneath the neck of the horn I 35 place a reinforcing post 27 which is permanently mounted on the partition 8 and has the upper end gouged out as indicated at 28 to fit accurately the underside of the neck. This post forms a solid support for 40 the base of the neck at the point where the sound waves are being deflected to the flaring end of the horn. In actual practise I form the post from a number of wooden strips securely fastened together such as by 45 nailing. This feature is not claimed herein but is made the subject of a separate application, Serial #498,387 filed Sept. 3, 1921.

In order to close off the back end of the horn chamber I have placed a vertical partition 30 across the chamber slightly in advance of the post and bracket and have cut the opening 31 in the partition to admit the horn, the opening being somewhat larger than the horn at this point. I then place a 55 fabric indicated at 32 between the horn and the side of the opening to close off the spaces and entirely separate the back of the chamber from the front.

I have found in machines which I have 60 constructed with an air shaft that there is a natural air draft established from the floor upwardly through the shaft to the passage 26, such being due to the difference in levels. However, if it is desired to have a more or 65 less strong draft one can place an electric

fan indicated at 29 at the bottom of the passage and produce a forced draft upwardly through the air shaft and the passage 26 into the horn.

When a machine equipped with my invention is in use the air supplied through the air shaft materially enhances the quality, pitch and loudness of the sound emanating from the horn.

What I claim as my invention is:—

1. The combination with the delivery end of the sound box tube of a talking machine and a horn having the receiving end thereof spaced from the delivery end of the sound box tube to provide an air inlet opening of 80 an air shaft communicating with the inlet opening.

2. The combination with the delivery end of the sound box tube of a talking machine and a horn having the receiving end thereof surrounding but spaced from the delivery end of the tube to provide an air entrance 85 between the tube and the horn at the receiving end of the horn, of an air shaft built in the body of the machine and communicating with the air passage and with exterior air.

3. In a talking machine, the combination with the horn chamber, a horn mounted in the chamber and a sound box tube entering the chamber and extending into the receiving end of the horn, but spaced therefrom to provide an annular air inlet passage 95 surrounding said tube of an air shaft opening to the horn chamber.

4. In a talking machine, the combination with a case, a horn and a sound box tube, of a bracket permanently secured to the back of the case and receiving and supporting the receiving end of the horn, an 100 upwardly flaring tube carried by the bracket and located at the receiving end of the horn and continuous therewith and an open ended stationary cylindrical tube continuous with the delivery end of the sound box tube and entering the flaring tube and of smaller diameter than the flaring tube to provide an 105 inlet passage to the horn and surrounding the cylindrical tube.

5. In a talking machine, the combination 115 with a case, a horn and a sound box tube, of a horizontally disposed bracket permanently secured to the back of the case and receiving the receiving end of the horn, an upwardly flaring tube permanently seated in 120 the top side of the bracket and having the lower end engaging the horn and with an internal diameter equal to the internal diameter of the receiving end of the horn and an open ended cylindrical tube continuous 125 with the delivery end of the sound box tube and having the lower end thereof entering but spaced from the inner wall of the flaring tube, thereby providing an annular inlet passage between the tubes.

6. In talking machines, a tone arm, and an amplifying horn, the large end of the tone arm ending adjacent the small end of the horn in acoustic relation to each other but spaced apart without physical connection therebetween, whereby extraneous air is admitted to the horn at this point without encountering obstructions of any kind.

7. In talking machines, a tone arm, an amplifying horn in a spaced apart acoustic relation to the tone arm forming an annular opening between them, a sound box on the tone arm adapted to produce sound waves for transmission through the tone arm across the space into the horn, and means external of the horn for encircling such sound waves by an enclosing and comingling column of air at the end of the tone arm and delivering the combined sound waves and air to the horn.

8. In talking machines, a tone arm, a horn having its receiving end spaced apart from the tone arm but in acoustic relation therewith, means for supporting said members in operative relation to each other extraneously of the adjacent ends of said horn and arm whereby an unobstructed air passage is formed between them, a communicating air passage in connection with the former, and means for conveying air through such passages to the horn.

9. In talking machines, a tone arm, a

horn having its receiving end in acoustic relation though physically disconnected from the tone arm, and means for supporting said members in operative relation to each other extraneously of the adjacent ends of said horn and arm whereby an unobstructed air passage is formed between them.

10. In talking machines, a support for the large end of a tone arm, a separate support for the small end of an amplifying horn, a tube connected to the tone arm, a tapering collar placed within the receiving end of the horn, and means for supporting the parts in such relation as to hold the receiving end of the tube within the collar but spaced apart from said collar to provide an obstructed air passage therebetween.

11. In talking machines, a tone arm, a support for its large end, a horn, a support for the small end of said horn, and means for coordinating such supports by attaching them to a member common to both so as to leave the arm and horn in acoustic relation to each other while their adjacent ends are physically disconnected.

Signed at Winnipeg, this 20 day of September 1918.

BAGSTER ROADS SEABROOK.
